UNITED STATES PATENT OFFICE.

WILLIAM J. DRYDEN, OF ST. LOUIS, MISSOURI.

NECKTIE-TURNER.

No. 884,911.

Specification of Letters Patent.

Patented April 14, 1908.

Application filed December 26, 1907. Serial No. 408,138.

To all whom it may concern:

Be it known that I, WILLIAM J. DRYDEN, a citizen of the United States, and resident of St. Louis, Missouri, have invented certain new and useful Improvements in Necktie-Turners, of which the following is a specification containing a full, clear, and exact description, reference being had to the accompanying drawings, forming a part hereof.

10 My invention relates to a necktie turner, my object being to construct a simple device and apparatus to be utilized in turning or reversing the bodies or outer coverings of neckties, and to provide means for conveniently holding the necktie lining or padding so that when the body or covering of the tie has been turned the lining or pad is properly positioned therein.

15 A further object of my invention is to construct a necktie turner with lining engaging devices which hold the lining at both ends, and one of which devices is adjustable for linings of different lengths.

20 A further object of my invention is to generally improve the construction of the device described in an application for patent filed by me October 8, 1907, Serial No. 396,506.

25 To the above purposes, my invention consists in certain novel features of construction and arrangement of parts, which will be hereinafter more fully set forth, pointed out in the claims, and illustrated in the accompanying drawings, in which;

30 Figure 1 is a perspective view of a necktie turner of my improved construction; Fig. 2 is a plan view of a portion of the turning blade or plate, and showing the adjustable clamp or engaging device thereon; Fig. 3 is a longitudinal section taken on the line 3—3 35 of Fig. 2; Fig. 4 is a plan view of the forward end of the turning blade or plate.

35 Referring by numerals to the accompanying drawings:—1 designates a base, in the form of a rectangular block, supported on 40 legs 2; and in one side of said base, near the top, is formed a horizontally disposed opening 3, and immediately below this opening is a small opening 4.

45 5 designates the body of the turner, which is in the form of an elongated plate, corresponding in shape to the shape of the ties to be turned; and formed integral with the forward end of said plate is a prong 6. Fixed to the rear end of the plate is a cylindrical handle 7, which is adapted to snugly fit in the opening 3, thereby holding the turner in a

horizontal position. Arranged to slide longitudinally on the plate, adjacent the handle 3, is a clamp or engaging device, comprising a plate 8, which rests on top of the plate 5, 60 with its side edges 9 bent beneath the edges of said plate 5. Integral with the rear end of the plate 8 is an ear 10, by means of which said plate is shifted; and fixed on top of the plate, in any suitable manner, is a housing 11, 65 in which is held a flat spring 12, the free end of which normally bears on the cross bar 13 of a clamping plate 14, which, when swung downward into a horizontal plane, bears on the ends of the tie linings positioned on the 70 plate 5. Detachably seated in the opening 4 is a rod or rail 15, which serves as a support for the tie linings and coverings.

75 When a turner of my improved construction is in use, the handle 7 is inserted in the opening 3, thus rigidly supporting the plate 5, and a pad or tie lining is positioned on top of said plate 5, with the narrow end of said lining engaged on the prong 6, and the opposite end held beneath the spring pressed 80 clamping plate 14.

85 The small end of the tie covering, which is in tubular form and wrong side out, is now engaged upon the prong 6; and said covering is slipped over the plate 1 on which the lining 85 is held; and by said movement the covering or body of the tie is reversed or turned right side out; and when the turning operation is completed, the lining or pad is properly positioned inside the covering. The clamping 90 plate 14 is now elevated to release the end of the tie lining, and said lining and the tie covering are now removed from the plate.

95 By the use of a device of my improved construction, the turning operation can be very rapidly performed, thus saving much time, labor, and expense in the manufacture of neckwear, and the tie linings are held in convenient position on the plate, with both ends engaged, and one of the engaging devices is 100 adjustable for tie linings of different lengths.

I claim:—

1. In a necktie turner the combination with a base in which is formed an aperture, of a plate, one end of which is seated in the 105 aperture, a prong integral with the opposite end of the plate, and a clamp adjustably arranged on that portion of the plate adjacent the end which is seated in the base.

2. In a necktie turner, the combination 110 with a base in which is formed an aperture, of a plate, a handle formed on one end of the

plate, which handle is detachably arranged in the aperture in the base, a prong integral with the opposite end of the plate, and a clamp adjustably arranged on the plate adjacent the handle.

3. In a necktie turner, the combination with a base in which is formed an aperture, of a plate, a handle formed on one end of the plate, which handle is detachably arranged in the aperture in the base, a prong integral with the opposite end of the plate, a clamp adjustably arranged on the plate adjacent the handle, and a rod having one end seated in the base adjacent the handle of the plate.
- 10 4. In a necktie turner, the combination with a base in which is formed an aperture,

an elongated plate tapering from one end to the other, a handle formed on the wide end of the plate and which handle is seated in the base, a prong on the opposite end of the plate, 20 an adjustable clamp arranged on the plate adjacent the handle, and a supporting rod seated in the base and lying parallel with the plate.

In testimony whereof, I have signed my 25 name to this specification, in presence of two subscribing witnesses.

WILLIAM J. DRYDEN.
